UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF MISSOURI.

LOCOMOTIVE CRADLE AND ASH PAN.

Application filed September 14, 1925. Serial No. 56,217.

My invention relates to railway rolling stock and consists in the construction of an ash pan, such as is used under the fire box, integrally with a vehicle body frame member. An obvious embodiment of my invention is in a locomotive cradle and ash pan formed integrally. Preferably I form these members in a one-piece casting, but they could be otherwise formed integrally.

10 The objects of my invention are to provide a rigid structure of light weight and at low cost and to eliminate the necessary machining and fitting and other delay and expense involved in the production and assembling of separate cradle and ash pan units.

In the accompanying drawings illustrating my invention—

Figure 1 is a longitudinal top view of one-half of a locomotive cradle and ash pan embodying my invention, showing the rear end of a locomotive bed.

Figure 2 is a side elevation of the same, showing the rear driver, trailer wheel, and mud ring.

Figure 3 is a vertical transverse section on line 3—3 of Figure 2.

Figures 4 and 5 are similar cross sections illustrating modifications of my invention.

30 In the drawings, the rear end of the locomotive main bed is indicated at 1, the same terminating near the rear pedestal 2 and having bolted thereto the rearwardly projecting cradle comprising side members 3, a front transverse member 4, a rear transverse member 5, a foot plate 6, a draw-bar pocket 7, side bearing brackets 8, brake hanger lugs 9, and brackets 10 to which plates P may be secured for supporting the mud ring M. Each of the cradle side members 3 includes a vertical wall 11, and inwardly facing top and bottom flanges 12 and 13, respectively. Preferably a portion of the member 3 will be provided with outwardly facing ribs 14 throughout a substantial portion of its length but, disregarding these ribs, the side member is substantially channel-shape in cross section.

Formed integrally with member 3 is a vertical element 15 extending across the inner ends of flanges 12 and 13 and projecting below lower flange wall 13 for a portion of the length of member 3 to form the depending side wall 16 of an ash pan, preferably reinforced with ribs 16a. Throughout

a substantially larger portion of the entire length of member 3, element 15 projects upwardly and outwardly to form the laterally extending portion 17 of an ash pan. The end walls 18 of the ash pan extend across the space between the members 3, bracing them to each other at points intermediate transverse members 4 and 5.

Each of the cradle side members between the front and rear walls of the ash pan is substantially box-shape in cross section and the ends of this portion of the member are left open to permit the free circulation of air through the same to avoid undue heating and weakening of the main vertical wall 11 of member 3. Additional openings 19 may be provided in member 3 to increase the circulation of air, but these are optional.

With the above described construction, the ash pan and cradle are formed complete in one casting, and in this unitary structure the cradle and ash pan reinforce each other so that greater strength is secured with the thicknesses of material heretofore used, or the various elements may be reduced in thickness and weight and their previous strength maintained.

While in my preferred structure I illustrate the complete ash pan formed integrally with the cradle, it may be desired to form the ash pan hopper only or the upper portion of the ash pan only with the cradle, and in Figure 4 I illustrate the first of these modifications, the main side member 20 of the cradle having a downwardly projecting element 21 forming the lower side wall of the ash pan similarly to element 16 in the preferred structure. The upper portion 22 of the ash pan is shown as bolted to the cradle side member 20 and therefore detachable from the cradle.

In Figure 5 I illustrate the other modification referred to in which the lower portion 23 of the hopper is bolted to the cradle side member 24. The upper portion 25 of the ash pan is formed integrally with the cradle member 24, its lower portion extending across the inner ends of the flanges of member 24 to form a smooth inner surface and protect the main wall 26 of member 24 from excessive heat.

While I have illustrated my invention as embodied in a cradle ash pan which is a complete unit, applicable to and removable from the remainder of the locomotive superstruc-

ture, the ash pan could be formed integrally with a locomotive bed or main frame which did not terminate at the drivers but projected rearwardly beyond the fire box.

5. My invention consists broadly in the formation of one or more ash pans integrally with a portion of the body of the vehicle superstructure. In my copending applications, Serial Numbers 56,215 and 56,216 of 10 even date herewith I describe and claim the formation of ash pans integrally with truck frame members as distinguished from the formation with a body member, and I contemplate in the commercial development of 15 my invention all embodiments thereof, distinguished from the truck structures referred to, as are included in the scope of the appended claims.

I claim:

20. 1. In a railway vehicle body frame, a portion forming part of an ash pan.
2. In a railway vehicle body frame, a vertical surface forming part of an ash pan.
3. A railway vehicle body member having 25 an integral downward projection forming the side of an ash pan.
4. A railway vehicle body member having an integral upward projection forming the laterally extending portion of an ash pan.
30. 5. A railway vehicle body member having integral upward and downward projections forming, respectively, the upper and lower portions of an ash pan.
6. A railway vehicle longitudinal frame 35 member box-shape in cross section with the top and bottom and one side wall forming stress-resisting elements and with its other side wall forming part of an ash pan.
7. A railway vehicle longitudinal frame 40 member box-shape in cross section with the top and bottom and one side wall forming stress-resisting elements and with its other side wall projecting above the top of the box-section and forming the upper portion 45 of an ash pan.
8. A railway vehicle longitudinal frame member box-shape in cross section with the top and bottom and one side wall forming stress-resisting elements and with its other 50 side wall projecting beyond the bottom of the box section and forming part of an ash pan hopper.
9. A railway vehicle longitudinal frame member box-shape in cross section with the 55

top and bottom and one side wall forming 60 stress-resisting elements and with its other side wall projecting above and below the box section and forming the side of an ash pan and hopper.

10. A locomotive cradle and ash pan 65 formed integrally.

11. A locomotive cradle and ash pan hopper formed integrally.

12. A one-piece casting comprising a locomotive cradle and ash pan.

13. A one-piece casting comprising a locomotive cradle and ash pan sides and ends.

14. A one-piece casting comprising a locomotive cradle and an ash pan hopper.

15. A one-piece casting comprising a locomotive cradle and the upper sides of an ash pan.

16. A locomotive cradle having a portion of each side box-shape in cross section with its inner wall forming part of an ash 75 pan, said portion having open ends to permit the passage of air therethrough.

17. A locomotive cradle having a portion of each side box-shape in cross section with its inner wall forming part of an ash pan, 80 said portion having one or more of its other walls perforated at intervals to admit air to the exterior of said ash pan forming wall.

18. In a one-piece casting, longitudinal cradle sides and ash pan end walls extending transversely of and uniting said sides.

19. In a one-piece casting, longitudinal cradle sides and ash pan end walls extending transversely of and uniting said sides, and depending ash pan walls below the level 90 of said sides.

20. A one-piece casting comprising a locomotive cradle with an ash pan and draw-bar pocket formed integrally therewith.

21. A one-piece casting comprising a locomotive cradle with spaced side members, transverse ash pan end walls uniting said members, and transverse end members spaced from said ash pan walls and uniting 95 said members.

22. A one-piece casting comprising a locomotive cradle with outwardly projecting side bearing brackets and ash pan extensions formed integrally.

In testimony whereof I hereunto affix my 105 signature this 9th day of September, 1925.

H. M. PFLAGER.
